UNITED STATES PATENT OFFICE.

LEONARD M. RANDOLPH, OF NEWARK, NEW JERSEY.

RAILWAY-SWITCH.

SPECIFICATION forming part of Letters Patent No. 612,435, dated October 18, 1898.

Application filed March 12, 1898. Serial No. 673,555. (No model.)

To all whom it may concern:

Be it known that I, LEONARD M. RANDOLPH, a citizen of the United States, residing at Newark, in the county of Essex and State of New Jersey, have invented an Improvement 5 in Railway-Switches, of which the following is a specification.

The object of this invention is to allow the driver to turn the switch in either one direction or the other previous to the car arriving at such switch and to cause the actuating devices to remain normally below the level of the roadway and protected from the risk of injury from passing vehicles.

15 In the present invention the flange of the car-wheel as it passes along the grooved rail depresses a lever and acts upon a rod extending toward the switch, and in so doing two levers are elevated so as to be in a position to be acted upon by a downward projection fixed 20 adjustably upon the car or by a projection that may be operated by the conductor or motorman, so as to swing one of the levers and turn a swivel-plate from which a connection 25 extends to the switch-point, and the levers fall by gravity, so that in the normal position they are flush with the roadway and not liable to injury by horses or vehicles passing over the switch.

30 In the drawings, Figure 1 is a diagrammatic plan illustrating the positions of the respective parts. Fig. 2 is a sectional elevation, in larger size, of the levers and switch-tongue connection. Fig. 3 is a cross-section 35 at the line 3 3 of Fig. 2, and Fig. 4 is a cross-section at the line 4 4 of Fig. 2.

The track rails or bars are illustrated at K, and the switch-point H is pivoted at 14 and serves to direct the car upon the main track 40 or turn the same off upon the side or branch track, and at A is a lever with an arm or bolt 2 extending up through a mortise in the rail and in a position close to the tread of the rail, so as only to be acted upon by the flange 45 of a wheel as such wheel passes along the track with its flange or rim in the groove of the track.

The rod B is connected with the lever A, and it extends to the levers C D, and it has a 50 T head or end 5 for acting upon the lower portions of the levers C and D and bringing the upper portions of such levers C and D

vertical, or nearly so, these levers C D being pivoted at 6 to the top part of a box M, and in this box is the swivel-plate E, supported 55 on a suitable pivot 7 and having latch-lugs or projections 8 and 9, and such plate E can be turned freely upon its central support and has a rod F extending to the switch, or nearly so, and to which it is connected by 60 any suitable mechanism—such, for instance, as the turning-plate or lever G, that extends to or is connected at its end with the switch-point. The lever C acts at one side of the pivot 7 and the lever D acts at the other side. 65

It will now be understood that in the normal position of rest the lever A is in the position indicated in Fig. 1, with its upper end 2 closely adjacent to the surface or tread of the track-rail, and when a car passes along 70 upon such track-rail the flange of the car-wheel acts upon the upper end and moves the lever A and gives end motion to the rod B, so that the T-head thereof, acting below the pivot 6 upon the levers C and D, swings them 75 up into a substantially vertical position, and one of the levers C or D engages one of the latch-lugs 8 or 9 upon the swivel-plate E, and the other lever drops back into its place as the rod B is withdrawn by the spring 12, there 80 being no latch projection in a position to engage the lower end of such lever. Hence if the lever D falls the end of the lever C is adjacent to the latch or projection 9 upon the swivel-plate E, and as the car comes along 85 the driver with any suitable instrument or by a fixture to the car acts upon the lever C and gives a motion thereto, turning the swivel-plate and swinging the lever down and out of use. During this operation a rod F, connected 90 with the swivel-plate E, receives a motion and communicates the same to the plate or lever G, that is pivoted upon a suitable support and has a connection from one end to the switch-point H, such connection being preferably in the form of a bar or link 10, extending along beneath the track and engaging the downward projection upon the switch tongue or bar H. 95

It will be understood that the spring 12, 100 that is connected with the rod B, draws back such rod as soon as the wheels pass beyond the lever or pusher A, so as not to act upon the same, and it is also advantageous to have

a spring 13 near the **T** head or end of the rod B to aid in holding up the rod at this end. Hence said rod B assumes the normal position with promptness and is not acted upon 5 after the car has passed beyond the lever A.

If the swivel-plate E and the switch-point are in the reverse position to that represented, the lever D will engage the projection 8 upon the swivel-plate E when the levers C 10 and D are turned up, and in this case the lever C, not being held by the latch on the swivel-plate, immediately drops as the lever A and rod B return to a normal position.

It is advantageous to place the lever A in 15 a box below the track and to provide a pipe B', surrounding the rod B and extending to the box M, and the cover of this box M is at the surface of the roadway, or nearly so, and is provided with slots for the upper parts of 20 the levers C and D, and this cover can be removable and attached to the box by bolts, and it is generally advantageous to support the levers C and D between the ears upon the cover of the box M, with a pivot-pin or screw 25 6 passing through the ears below the top of the cover.

A pipe F' should extend from the box M to the box N, containing the bent lever or plate G, which is pivoted at 14, and the end of the 30 rod F is connected with this bent lever or plate, and the connection 10 is also pivoted at one end upon this lever or plate and is connected at the other end to the switch-point H.

In the box N there is preferably a grating 35 or perforated support for the pivot 14 in order that sand or other solid materials may drop down below such grating or support, and there should also be a pipe leading to a sewer in cases where water is liable to run into this 40 box N, and the same provision should be made for the box M when needed.

It will often occur that either the lever C 45 or D will remain in an upright position after the car has passed, because the switch may be in the right position, and it would not in that case be necessary for the driver or motorman to act upon such lever C or D to turn the switch, and it would be disadvantageous to have this lever C or D standing upright in 50 the roadway. To prevent this, the swivel-plate E is held up by a spring 20, which advantageously surrounds the pivot of such swivel-plate, and there is a depressing-bar 21 with an eye around the pivot-pin of the 55 swivel-plate E, and the other end of this depressing-bar passes up through a mortise in the track-rail, so that as the car passes along the wheel-flanges depress the bar 21, forcing the spring 20 down and allowing the swivel- 60 plate E to drop sufficiently for the latch thereupon to be clear from the lower end of the lever C or D, so that such lever falls back into its normal horizontal position, the shape of such lever C or D being such that it will

fall rapidly and by gravity as soon as the 65 lower end of such lever is disconnected from the latch on the swivel-plate, and a second spring 22 may be applied below the depressing-bar 21, if desired, to equalize the lifting action in restoring the parts to a normal position. 70

It will be understood that if the latch-lugs 8 and 9 are provided with springs the lower end of the lever C or D will depress the latch-lug as the levers are swung up vertically; 75 but when the latch-lugs 8 and 9 are rigid with the swivel-plate the spring 20 allows such swivel-plate to be pressed down by the contact of the lever with the inclined surface of the latch-lug, and the plate rises as the end 80 of the lever clears the latch-lug, so that the lever can act against the lug in turning the swivel-plate and setting the switch.

I claim as my invention—

1. The combination with the switch-point 85 and the lever and rod for turning the same, of a swivel-plate to which one end of the rod is connected, latch projections upon the swivel-plate, levers pivoted above the swivel-plate, a lever and depressing device at a sufficient distance from the switch, a push-rod 90 with a **T**-head for swinging the swivel-plate levers into a vertical position to be acted upon as the car passes to set the switch when necessary, substantially as set forth. 95

2. The combination with the swivel-plate and the movable switch-point, of an intervening connection for moving the switch-point when the swivel-plate is partly turned, a pair of levers adapted to act at opposite sides of 100 the pivot of the switch-plate and upon latch-lugs upon the swivel-plate, and means for swinging up the levers into position to be acted upon by the driver or motorman of the car for setting the switch in the desired direction, substantially as set forth. 105

3. The combination with the switch, of a swivel-plate and connection between the switch and swivel-plate, levers for acting upon the swivel-plate, a spring for supporting the swivel-plate, and a depressing-bar acting against the spring to allow the swivel-plate to descend and disconnect the latch projections upon the swivel-plate from the levers, substantially as set forth. 115

4. The combination with the switch-point and mechanism for changing the position of the same, of two levers, a push-rod and **T**-head acting upon said levers and mechanism for moving the **T**-headed rod endwise automatically by the passing wheels and elevating the levers into position to be acted upon by the passing car, substantially as set forth. 120

Signed by me this 5th day of March, 1898.
L. M. RANDOLPH.
